METHOD OF MAKING HOLLOW POPPET VALVES

Archie T. Colwell, Cleveland, Ohio, assignor to
Thompson Products, Inc., a corporation of Ohio

Application January 24, 1944, Serial No. 519,435

2 Claims. (Cl. 29—156.7)

1

This invention relates to poppet valves having cast corrosion-resistant metal head ends and forged stress-resistant and wear-resistant metal stem ends.

Specifically the invention relates to a hollow poppet valve having a hollow cast corrosion-resistant metal head portion defining the hollow valve head, the hollow valve neck, and a portion of the hollow valve stem together with a hollow stress-resistant and wear-resistant forged metal stem portion welded to the cast portion throughout a weld band of greater area than the cross-sectional area of the stem and located well down the length of the valve stem to be out of corroding atmospheres surrounding the valve head and neck in operation of the valve. The invention includes a process for preparing these valves.

In accordance with this invention a casting mold is provided with a mold cavity in the shape of the head end of a poppet valve. This cavity includes a poppet valve head-defining portion, a poppet valve neck-defining portion, and a segmental poppet valve stem-defining portion. A frangible core composed of ceramic material, baked core binder impregnated sand, or the like, and having a cylindrical stem portion and an enlarged mushroom-shaped head end portion is suspended in the mold to project in the mold cavity in equally spaced relation from the walls thereof. A gate is provided in the mold surrounding the stem portion of the suspended core and communicating with the end of the stem-defining portion of the mold cavity. Metal is poured into the mold cavity around the core to produce a hollow casting from which the frangible core is readily removed. This casting is in the form of a hollow head end of a poppet valve and, in one method of casting, has a short stem portion terminating in the gate. The gate is cut from the stem portion of the casting and the end face of the casting from which the gate was cut is smooth-finished and preferably polished to present a clean, smooth, flat rim end on the casting.

The casting is preferably composed of corrosion-resistant alloys. For example, castings composed of highly corrosion-resistant metal such as: nickel, chromium and iron alloys; nickel, molybdenum and iron alloys; non-ferrous nickel-chromium alloys; and chromium-tungsten alloys

2

can be used for effectively resisting the corroding gases and vapors in the combustion chamber of an internal combustion engine. Many such alloys with highly desirable heat and corrosion-resistant properties cannot be forged.

5 A hollow forged tube of a high strength abrasion resistant alloy is provided with a clean, smooth and preferably polished rim end. An alloy which has good resistance to valve stem guides is preferred. High heat conductivity properties are also preferred. A very suitable alloy is a tungsten steel known as S. A. E. 71360 and containing 0.50 to 0.70% carbon; 3 to 5% chromium; 12 to 15% tungsten; 0.3% manganese, and the balance iron.

The tube can be hardened, as by nitriding, if desired.

20 The clean, smooth rim ends of the casting and the tube are mated together in full contacting relation, and pressure is applied to hold the contacting surfaces together for sealing them against air, dirt and the like. Pressures of about 300 pounds per square inch of contacting surface can be used and, in some instances, these pressures may be as high as 2000 pounds per square inch.

25 A flame torch head is enveloped around the pressed-together members and welding flames are impinged on the members in the vicinity of the contacting surfaces to heat these surfaces by conduction radially inward from their peripheries to welding temperatures. Temperatures between 1000° C. and about 1300° C. can be used, but in no event should the metals be heated to their melting points.

30 35 A pressure weld is thereby produced and the contacting surfaces assume a concavo-convex relationship and are somewhat upset both on their inner and outer peripheries to form bulges or beads.

40 45 A feature of the invention is the provision of a weld area between the cast member and the forged tube which is of greater area than the cross-sectional area of either contacting surface even when the bulges or beads are removed. Because of this increased area, a stronger bond is obtained.

Since the entire welding operation is carried out with the surfaces sealed together, no burning of the metal and no flashing of the metal will occur.

It is, then, an object of this invention to provide poppet valves having cast corrosion-resistant head end portions extending well down into the stem of the valve and welded to forged stress-resistant and abrasion resistant stem portions along a weld line of greater area than the cross-sectional area of the welded-together parts.

A still further object of the invention is to provide composite hollow poppet valves having head ends composed of highly corrosion-resistant alloy and stem ends composed of wear-resistant metals with the head ends and stem ends integrally pressure-welded together at a point intermediate the ends of the stem portion of the valve.

A still further object of the invention is to provide a poppet valve having a cast corrosion-resistant metal hollow head portion and a wear-resistant metal stem portion welded over an increased area to the head portion in spaced relation from the neck of the valve so that in use of the valve the cast metal will be the only part of the valve exposed to the corroding atmosphere in the combustion chamber of an engine and the stem will resist abrasion of the valve guide.

A further object of the invention is to provide a process for making composite poppet valves having a cast heads and forged stems including pressure welding of the heads and stems into integral unitary relation.

A still further object of the invention is to produce a composite poppet valve having a head end portion and a stem end portion integrally joined along a sharply defined weld line positioned so that, in use of the valve, it is within the valve guide and not exposed to corroding atmospheres.

Other and further objects of the invention will be apparent to those skilled in the art from the following detailed description of the annexed sheet of drawings which, by way of preferred example only, illustrates one embodiment of the invention.

On the drawings:

Figure 1 is an elevational view of a half of a casting mold for making cast head members for valves according to this invention and illustrating the manner in which a frangible core is suspended in the mold cavity.

Figure 2 is an elevational view, with parts shown in vertical cross section, of a cast valve head and a forged valve stem tube mounted in apparatus for pressure-welding the head and tube together.

Figure 3 is an axial cross-sectional view of a valve blank produced according to this invention.

Figure 4 is an enlarged axial cross-sectional view of the weld area of the blank of Figure 3.

Figure 5 is an axial cross-sectional view of a completed poppet valve made according to this invention.

As shown on the drawings:

In Figure 1, the reference numeral 10 designates half of a permanent casting mold having dowel pins 11 projecting therefrom to receive a mating half of the mold (not shown). The mold 10 has a mold cavity 12 therein defining a valve head forming portion 12a, a valve neck forming portion 12b, and a segmental valve stem forming portion 12c. A gate cavity 13 is formed in the mold communicating with the top end of the stem forming cavity portion 12c. This gate cavity 13 has an upwardly curved laterally extending passageway 13a communicating with the lower end of a pour hole 14 for the mold.

The mold 10 also has a core suspension cavity 15 above the gate cavity 13, and a frangible core 16 is clamped in this cavity 15. The core 16 extends through the gate cavity 13 and has a cylindrical stem portion 16a and an enlarged mushroom-shaped head portion 16b suspended in the mold cavity 12 in spaced relation from the walls thereof.

Metal is poured through the pour hole 14, gate 10 passage 13a, and gate 13 into the mold cavity around the core 16 to form a hollow casting 17. This casting 17 is readily removed from the mold by separating the mold into its component halves. The core 16, being composed of frangible material, is readily broken out of the casting and the gate 13 formed in the gate cavity 13 is cut off from the casting.

As shown in Figures 2 and 3, the casting 17 has a domed head portion 17a with a central 20 projecting lathe-centering lug 17b, a beveled side wall portion 17c, a curved neck portion 17d, and a cylindrical fragmental stem portion 17e. The casting 17 has a cylindrical cavity 19 in the stem portion 17e and an enlarged mushroom-shaped 25 head cavity 20 communicating with the stem cavity 19. The cavities 19 and 20, of course, are formed by the core 16.

The end of the stem portion 17e terminates in an annular rim 17f as shown in Figure 2 which is 30 smooth finished as by grinding and polishing to a clean flat surface.

The casting 17 is preferably composed of highly corrosion-resistant and heat-resistant alloys such as those specified hereinabove.

35 A forged cylindrical metal tube 21, preferably composed of forged stress-resisting and wear-resisting material, has a thickened nubbin end portion 21a on one end thereof and a flat clean smooth finish rim end 21b on the other end thereof. A straight cylindrical bore 22 extends through the tube 21.

As shown in Figure 2, the casting 17 is mounted in a base block 23 of a press 24. This base block 23 has a recess 23a therein snugly receiving the head dome 17a and the lug 17b of the casting so that the casting can be mounted in an upright position with the flat rim end 17f thereof disposed in a horizontal plane.

The press 24 also has a recessed block 25 receiving the nubbin end 21a of the tube 21 so that the tube depends vertically with the flat rim end 21b thereof resting on and mating with the flat rim 17f of the casting. The contacting rim ends 17f and 21b are pressed together in full contacting relation by the press 24 at high pressures which will seal the contacting surfaces.

A torch head 26 in the form of an annular ring envelopes the stem portion 17e of the casting 17 and the tube 21. This torch head 26 defines an annular gas chamber 26a receiving gases from a nipple 27. An oxygen supply tube 28 and an acetylene supply tube 29 are connected to the nipple 27 for supplying oxygen and acetylene to the annular passageway 26a.

65 The inner periphery of the torch head 26 has a plurality of small radial holes 26b therein providing jets for issuing gases from the chamber 26a around the entire periphery of the tube 21 and stem portion 17e of the casting 17. Jets of 70 flame 30 issue from the holes 26b and impinge upon the casting and tube to heat the contacting surfaces 17f and 21b radially inward from their outer peripheries to welding temperature. As indicated by the arrows 31 the torch head 26 is 75 reciprocated axially along an area of the stem

portion 17e and the tube 21 on either side of the contacting surfaces thereof. As indicated by the arrow 32, the torch head 28 is also oscillated during the reciprocation thereof so that the flame jets 30 will not constantly impinge upon the same spot of the tube and casting.

The oxy-acetylene flames impinge upon and heat the casting and tube adjacent the contacting surfaces thereof and heat is conducted by the metal radially inward along the entire contacting surfaces to bring these surfaces to welding temperatures. The temperatures of the surfaces will depend largely upon the type of metal to be welded, but suitable welding temperatures will never reach the melting points of the metal and are normally in the nature of 1000° C. to 1300° C.

Pressure from the press 24 is continually applied during the welding operation and, as shown in Figures 3 and 4, the metal on each side of the contacting surfaces is upset to form an outer bead 33 and an inner bead 34. During the heating, the contacting surfaces will be pressed down around their peripheries into a concavo-convex relationship and the weld line 35 produced by the pressure welding operation will have an arcuate contour which has a greater area than the area of the initially contacting surfaces even when the beads 33 and 34 are removed.

The blank of Figure 3 is thus produced and from this blank the finished valve 36 of Figure 5 is formed by machining and forging operations. Thus the thickened nubbin portion 21a of the tube 21 is inwardly collapsed to form a solid end 37 on the valve stem closing the valve cavity 38. This valve cavity receives coolant (not shown) such as metallic sodium or the like for dissipating heat from the head of the valve along the length of the valve stem. The beads 33 and 34 of the blank are machined off, but the final valve 36 still has the curved weld line 35 of greater area than the cross-sectional areas of either the cast stem portion 17e or the tube 21. This increased weld area is highly desirable to increase the strength of the bond between the cast head and the forged stem.

The valve 36 thus has a cast head portion 36a extending down through the neck of the valve to the weld line 35 which is intermediate the ends of the valve stem and is in spaced relation from the neck of the valve.

The remainder of the valve stem 36b is composed of the forged stress-resistant and wear-resistant metal from the tube 21. The stem portion 36b of the valve does not extend into chambers containing corrosive gases when the valve is in operation in an engine, since the cast part of the valve extends sufficiently down the length of the valve stem so that it is the only portion exposed to the corroding gases.

The beveled side wall 17c of the casting 17, as shown in Figure 5, can be recessed to receive a puddled-in or welded-in ring 39 of alloy steel to provide a seating face for the valve.

From the above descriptions it will be understood that this invention provides a poppet valve having a hollow head end, a hollow neck portion, and a hollow short stem portion composed of cast corrosion-resistant metal together with a forged main stem portion, having stress- and wear-resistance, welded to the stem portion of the head by a pressure-welding operation to produce a bond area of greater cross-sectional area than the stem portion.

In use of the valves of this invention as ex-

haust valves for internal combustion engines, the corrosive gases surrounding the valve head and valve neck do not reach the forged stem portion of the valve because the weld area is spaced sufficiently from the neck of the valve to be in or near the valve stem guide and not exposed to the gases. The stem metal being wear resistant will withstand abrading action of the guide and, being highly heat conductive, will dissipate heat from the valve head. The weld between the stem and head portions is sharp and uniform with an area greater than the transverse cross section areas of either the stem or head at the weld line. The increased area caused by pressure welding produces a stronger bond.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. The method of producing composite hollow valves having cast hollow head ends and forged hollow stem ends which comprises forming a hollow heat and corrosion resisting alloy casting having a hollow poppet valve head and neck with a cylindrical stem portion extending from the neck and having a flat end face, forging a strong abrasion resisting steel blank to form a hollow cylindrical tube with a thickened end portion and a reduced-diameter stem-defining portion with a flat end face, cleaning the flat end faces of the reduced-diameter stem defining portion of the tube and the stem portion of the casting, axially pressing said end faces together into full contacting relation under pressures from about 300 to 2000 pounds per square inch of contacting surface, impinging flames around the casting and tube on each side of the contacting surfaces for heating said surfaces by conduction to temperatures from about 1000° C. to about 1300° C., continuing the application of pressure on said surfaces during said heating for deforming and pressure welding the surfaces together along an arcuate weld line of greater area than the area of the initial contacting surfaces, machining the resulting blank into final poppet valve shape, and inwardly collapsing the thickened end portion of the tube part of the blank to seal the hollow interior of the valve.

2. The method of making hollow poppet valves which comprises forming a casting of highly corrosion-resistant metal having a hollow poppet valve head portion, a curved converging hollow neck portion, and a short hollow cylindrical stem portion having a flat end face, cleaning and polishing the flat end face of said stem portion of the casting, forming a hollow tube of forgeable steel with a flat end face, cleaning and polishing a flat end face of said tube, axially pressing the cleaned and polished end faces of the tube and casting together under pressures sufficient to seal the contacting surfaces, and heating the casting and tube in the vicinity of the contacting surfaces while said surfaces are being pressed together to temperatures sufficiently high for welding the surfaces and thereby producing a composite valve blank having a cast corrosion-resistant head portion extending into the stem portion of the valve and a forged stress-resisting hollow stem welded to the head portion throughout a curved area of greater size

than the thickness of either the stem portion of the casting or the tube at the weld line.
